CLAIM

The ornamental design for a metal handrail with braille insert, as shown and described.

DESCRIPTION

FIG. 1 is a perspective view of a metal handrail with braille insert showing my new design;

FIG. 2 is a fragmentary front elevational view thereof;

FIG. 3 is a fragmentary top plan view thereof;

FIG. 4 is a fragmentary rear elevational view thereof;

FIG. 5 is a fragmentary bottom view thereof; and,

FIG. 6 is a side elevational view thereof.

The broken lines disclosing braille are for illustrative purposes only and form no part of the claimed design.

FIG. 1

FIG. 6

FIG. 2

FIG. 3

FIG. 4

FIG. 5
